UNITED STATES PATENT OFFICE.

CARL HENRY WILLIAMS, OF BUFFALO, NEW YORK.

VENTILATOR.

1,128,085.

Specification of Letters Patent.

Patented Feb. 9, 1915.

Application filed October 17, 1913. Serial No. 795,691.

To all whom it may concern:

Be it known that I, CARL HENRY WILLIAMS, a citizen of the United States, residing at Buffalo, in the county of Erie and State of New York, have invented new and useful Improvements in Ventilators, of which the following is a specification.

This invention relates to the class of ventilators comprising a horizontal hood or cowl rotatably mounted on an air shaft or pipe and containing means for condensing the wind as it enters the hood, in order to increase the force of the draft through the ventilator and effectually withdraw the foul air from the air shaft.

The object of my invention is to improve such ventilators with a view of simplifying their construction, reducing their cost and increasing their efficiency.

20 In the accompanying drawings: Figure 1 is a longitudinal section of the ventilator. Fig. 2 is a front view thereof. Fig. 3 is a rear view of the same. Fig. 4 is a perspective view of the deflectors removed from 25 the hood and separated to more clearly show their construction.

Similar characters of reference indicate corresponding parts throughout the several views.

30 A indicates the horizontal, cylindrical hood or cowl of the ventilator which is open at both ends and preferably provided at its front end with the usual flaring mouth or wind-deflecting flange D and on its rear portion with the customary vane G, which may be stiffened by stay-wires G¹. On its underside the hood has the usual neck B communicating with its interior and overlapping the fixed upright air-shaft or pipe

35 C on which the hood is rotatably mounted by any suitable means. In the construction shown in the drawings, this neck carries internal braces or bridge-pieces j and k and the air shaft C carries similar bridge pieces 40 l and m, and an upright shaft H is suitably fastened to the upper bridge pieces j and k and journaled in the lower ones l and m.

45 Within the front or inlet portion of the hood A are located a plurality of wind deflectors E, F, F, arranged lengthwise of the hood and preferably having approximately the form of hollow conical sections the concave sides of which face the wall of the hood. Three of such deflectors are 50 shown in the drawings, the two deflectors F, F being located at opposite sides of the

hood, while the deflector E is arranged between the upper portions of said side-deflectors F. The apexes of the several deflectors meet approximately in the axis of 60 the hood near its inlet end, and from this point the deflectors diverge rearwardly and extend outwardly to the surrounding wall of the hood, their outer edges e and g being riveted or otherwise secured to the hood. 65 The deflectors are fastened to the interior of the hood only at their longitudinal edges, leaving draft passages or openings f between their curved rear ends and the wall of the hood. The contiguous sides of the 70 forwardly-converging deflectors are likewise fastened together at c and d.

The lower front portion of the hood below the deflectors E and F is tightly closed by a shield preferably composed of sections 75 N which meet in a vertical joint b and are respectively stamped integral with the side deflectors F to form downward extensions thereof. These shield sections may be soldered or otherwise fastened together at 80 their meeting edges while their outer edges may be likewise secured to the wall of the hood, thus forming with the deflectors E and F a water-tight covering over the upper end of the neck B and the air shaft C. 85

As shown, the side deflectors F preferably extend rearwardly to or somewhat beyond the rear side of the air shaft C to prevent water from dripping from the rear ends of the deflectors into said shaft. 90

In the use of the ventilator, the wind entering the front end of the hood passes between the deflectors E and F and the surrounding wall of the hood and escapes at the rear end of the hood, withdrawing the foul air from the air-shaft C. In passing through the open-ended flues formed between the deflectors and the hood, the wind is condensed or compressed and on emerging at the rear ends of the deflectors it is 95 allowed to expand, thereby materially increasing the force of the draft and the efficiency of the ventilator.

To obtain the best results, the hood A should be somewhat greater in diameter than 105 the air shaft C, so that the area of the spaces between the rear portions of the deflectors E and F and the lower rear portion of the hood will at least equal the area of the air shaft.

110 In some cases, only two deflectors may be employed, say the side deflectors F, and I

do not therefore wish to be limited to the use of three deflectors, nor to the particular details shown in the drawings as the same may obviously be modified within the scope 5 of the appended claims.

I claim as my invention:

1. A ventilator, comprising a rotatable, substantially horizontal hood open at both ends and provided on its underside with an 10 opening adapted to communicate with an air-shaft, and a plurality of wind deflectors arranged within the hood at different sides thereof, said deflectors consisting of approximately conical sections converging toward the inlet end of the hood, the wide 15 rear portions of the deflectors extending outwardly to the wall of the hood.
2. A ventilator, comprising a rotatable, substantially horizontal hood open at both 20 ends and provided on its underside with an opening adapted to communicate with an air-shaft, a pair of wind deflectors arranged within the hood at opposite sides thereof, and a third wind deflector arranged in the 25 upper portion of the hood between the first-named deflectors, said deflectors consisting of approximately conical sections converging toward the inlet end of the hood and the wide rear portions of the deflectors extending outwardly to the wall of the hood.
3. A ventilator, comprising a rotatable,

substantially horizontal hood open at both ends and provided on its underside with an opening adapted to communicate with an air-shaft, wind deflectors arranged within 35 the upper portion of the hood, said deflectors consisting of approximately conical sections converging toward the inlet end of the hood and having their wide rear portions extended outwardly to the wall of the hood, 40 and a wind and storm shield extending downwardly from the inlet ends of said deflectors to the bottom of the hood.

4. A ventilator, comprising a rotatable, substantially horizontal hood open at both 45 ends and provided on its underside with an opening adapted to communicate with an air-shaft, a pair of wind deflectors arranged within the hood at opposite sides thereof, and a third wind-deflector arranged in the 50 upper portion of the hood between the first-named deflectors, said deflectors consisting of approximately conical sections converging toward the inlet end of the hood, said side deflectors being provided at their front ends 55 with meeting shield sections which extend downwardly to the bottom of the hood.

CARL HENRY WILLIAMS.
